SPOON OR SIMILAR ARTICLE

Kae E. Jones, New York, N.Y., assignor to Welling Ware,
Inc., New York, N.Y., a corporation of New York

Application November 10, 1958, Serial No. 53,334

Term of patent 7 years

(Cl. D54—12)

Fig. 1 is a front view of a spoon or similar article, showing my new design.

Fig. 2 is a side elevational view thereof.

Fig. 3 is a back view thereof.

Fig. 4 is an enlarged fragmentary view illustrating in detail the ornamentation on the handle.

Fig. 5 is a sectional view taken on line 5—5 of Fig. 1, drawn to an enlarged scale.

The essential features of my design for spoon or similar article reside in the configuration of the handle in combination with the particular type of ornamentation as applied thereto.

I claim:

The ornamental design for a spoon or similar article, substantially as shown and described.
